UNITED STATES PATENT OFFICE.

FRANK STEWART, OF CHICAGO, ILLINOIS, ASSIGNOR TO THE STOCKHAM MANUFACTURING COMPANY, OF SAME PLACE.

DESIGN FOR A CLOCK-FRAME.

SPECIFICATION forming part of Design No. 30,606, dated April 25, 1899.

Application filed March 24, 1899. Serial No. 710,375. Term of patent 7 years.

To all whom it may concern:

Be it known that I, FRANK STEWART, a citizen of the United States, residing at Chicago, in the county of Cook and State of Illinois, 5 have invented and produced a new and original Design for a Clock-Frame, of which the following is a specification.

The accompanying drawing shows my design of a clock-frame in front elevation.

As shown in the accompanying drawing, 10 the leading or material feature of my design consists in the figure of a dragon A, carrying near its head end a wheel B and mounted by the figure of a sailor C, gripping handles on 15 the wheel with his hands and represented in

the attitude of steering. The face of a clock D shows at the wheel, which encircles it. The dragon is represented with raised wing, hiding from view the lower extremities of the sailor, and with erect tail, and the whole rises from 20 an ornamental base of general scroll shape.

Having described my invention, what I claim as new, and desire to secure by Letters Patent, is—

The design for a clock-frame, as herein 25 shown and described.

FRANK STEWART.

In presence of—

M. S. MACKENZIE,
H. J. FROST.
